(57) **CLAIM**

The ornamental design for a mounting apparatus for electronic displays, as shown and described.

DESCRIPTION

FIG. 1 is a front perspective view of a mounting apparatus for electronic displays showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof, shown with environmental elements in broken lines; and,

FIG. 9 is a rear perspective view thereof.

The broken lines shown in FIGS. 1-9 are included for the purpose of illustrating environmental elements only and form no part of the claimed design.

Metal surfaces are shown in FIGS. 1-9 with appropriate surface shading for metal. Synthetic resin or plastic surfaces are shown with stippling in FIGS. 1-9
